DOOR HANDLE AND LOCK PLATE UNIT

John R. Gerlach, 1461 Solar Drive,
Monterey Park, Calif. 91754

Filed July 29, 1970, Ser. No. 24,204

Term of patent 14 years

Int. Cl. D8—06

U.S. Cl. D8—170

FIG. 1.

FIG. 2.

FIG. 3.

FIG. 4.

FIG. 5.

FIG. 6

FIG. 1 is a front elevational view of the design for door handle and lock plate unit;

FIG. 2 is a side elevational view thereof;

FIG. 3 is a rear, elevational view thereof with functional mechanical parts removed;

FIG. 4 is a top plan view of the lock plate thereof looking in the direction of the arrows 4—4 in FIG. 1, the bottom plan view of the lock plate being substantially similar;

FIG. 5 is a top plan view of the door handle thereof looking in the direction of the arrows 5—5 in FIG. 1; and

FIG. 6 is a bottom plan view of the door handle thereof looking in the direction of the arrows 6—6 in FIG. 1.

I claim:

The ornamental design for a door handle and lock plate unit, as shown and described.
